UNITED STATES PATENT OFFICE.

EVAN E. HUGHES, OF MERIDEN, CONNECTICUT.

FLOOR-SURFACING MACHINE.

1,023,251.

Specification of Letters Patent. Patented Apr. 16, 1912.

Application filed June 1, 1908. Serial No. 435,939.

To all whom it may concern:

Be it known that I, EVAN E. HUGHES, a citizen of the United States of America, residing at Meriden, in the county of New Haven and State of Connecticut, have invented a new and useful Floor-Surfacing Machine, of which the following is a specification.

My invention relates to improvements in floor surfacing machines and consists essentially of a car suitable to run over a floor either forward or backward and at variable speeds, rotary grinding-cylinders, suitable means to support said cylinders on said car, and means to rotate said cylinders and to operate the car.

The objects of my invention are, first, to provide a simple durable and economical self-propelling machine that will, when run over a floor, grind it down to a perfectly smooth and even surface; second, to provide a machine of this kind that can be operated in either direction and in which the speed can be so regulated that said machine will satisfactorily perform its work according to the conditions under which it is being operated, that is, will act successfully on a floor which is more or less uneven and which may vary in hardness so that more abrasion is required in some places than in others; third, to provide such a machine that can be operated at any speed desired up to the maximum and either forward or backward with equal efficiency; fourth, to afford means in such a machine for readily governing both the propulsion and the grinding function of the same; and fifth, to produce a floor surfacing machine that is withal practicable and efficient.

I attain these objects by the means illustrated in the accompanying drawings in which—

Figure 1 is a view of one side of the machine showing part of the interior mechanism in dotted lines; Fig. 2 a view of the other side of said machine; Fig. 3 a longitudinal vertical section; Fig. 4 a plan view with the top removed; Fig. 5 an enlarged detail of a part of one of the grinding-cylinders showing the mode of fastening the grinding material thereto; Fig. 6 a perspective view of one of the grinding-cylinders; Fig. 7 a detail end view of one of the grinding-cylinders showing the method of adjusting the boxes; and Fig. 8 a detail view of the friction journal-box.

Similar figures refer to similar parts throughout the several views.

1 represents a suitable frame supported at the rear end on a pair of driving wheels 2 and at the front end on a pair of steering wheels 3. The wheels 3 are set in swivels having forwardly extending bars 4 to the forward ends of which is pivoted a cross-bar 5. To the lower end of a steering rod 6 is permanently attached a forwardly extending rod 7 which is pivotally attached to the cross-bar 5. It is by these means that my machine is steered, for when the steering rod 6 is turned, the rod 7 carries the cross-bar 5 in the direction it is required to go, which turns the wheels 3 on their swivels by means of the bars 4.

The axles 8 and 9 of the grinding-cylinders 10 and 11 respectively are journaled in boxes 12 which are adjustably fastened to arms 13 by being bolted thereto through slots 14 in said arms, and said boxes are so fastened in order to afford the necessary adjustment for the chains hereinafter to be described. The arms 13, four, in number, are arranged longitudinally, two on either side of the frame extending from the transverse center thereof, and are pivoted to said frame at points intermediate their ends designated as 15.

In the center of each side of the frame is a vertical slot 16 having a member 17 slidably mounted therein to which the arms 13 are pivoted at 18 through slots 19 in said arms. The purpose of the said slots 19 is to provide means for the necessary movement of the pivot 18 in the arms 13 necessitated by the arms swinging on pivots and inscribing arcs in their movements hereinafter to be described, otherwise the mechanism would be inoperative. To a shaft 20 journaled in the frame and just inside of the sides of said frame, are fastened two levers 21 the ends of which are turned outward to pass through vertical slots 22 in the frame. The outturned ends of the levers 21 are pivoted to the members 17. To the said shaft 20 is suitably fastened a treadle 23. Below the arms 13 are springs 24 which bear against said arms to force or tension them upward at the center and thereby hold the grinding-cylinders firmly against the floor. Thus it may be seen that when the treadle 23 is rocked forward the levers 21 force the members 17 downward in their slots thereby swinging the arms 13 on the

pivots 15 and against the resiliency of the springs 24, and raise the grinding-cylinders 10 and 11 from the floor. When the pressure on the treadle 23 is removed the weight 5 of the cylinders augmented by the force of the springs 24 will again bring said cylinders in contact with the floor.

Above the arms 13 and fastened to the body are small plates 25 the lower portion of 10 which are turned outward and tapped to receive vertically placed screws 26. These screws 26 act as gages for the grinding-cylinders 10 and 11, for they are designed to be and in practice are so adjusted that they 15 limit the upward movement of the arms 13 and consequently the downward movement of the grinding-cylinders and so prevent the latter from going into hollows and declivities in the floor upon which the machine is 20 being operated.

The motive power of my machine may be supplied by any suitable engine or motor operated either by hand or power, but I prefer to employ an electric motor, as 27, 25 mounted on the top of the frame and to which the electricity may be supplied from any convenient source (not shown).

28 represents the switch for turning on and off the current supplied and 29 the 30 starting-box the purposes of which are well-known in the art and constitute no part of my invention.

The power of the motor 27 is transmitted to a counter-shaft 30 by means of a sprocket-wheel 31 on the shaft 32 of the motor 27, a sprocket-wheel 33 on the counter-shaft and a sprocket-chain 34. On the counter-shaft 30 is a gear 35 that meshes with a gear 36 on a second shaft 37 whereby the 40 shaft 37 is rotated in a contrary direction to the rotation of the shaft 30. The shafts 30 and 37 are provided with sprockets 39 and 40, respectively, that operate, by means of sprocket-chains 41 and 42, sprockets 43 45 and 44 on the axles 8 and 9 of the grinding-cylinders 10 and 11. The grinding-cylinders consequently rotate in opposite directions to each other and toward the lower edge of the frame; or outwardly so as to 50 throw the dust they make in grinding into pans 45 provided to receive it. The dust from the pans 45 is drawn through pipes 46 by an exhaust fan 47, operated directly from the motor by means of sprocket-wheels 55 48 and 49 on the motor-shaft and fan-shaft respectively driven by a sprocket-chain 50, and discharged from such into a suitable receptacle 51.

On the free end of the counter-shaft 30 60 and inside of the frame is a disk 52 rotating with said shaft and being covered on its face with leather or some other suitable material. Bearing against the face of the disk 52 is a friction-pulley 53 which is 65 slid- ily mounted on a longitudinally extending

shaft 54 and splined thereto so that both rotate together. The shaft 54 runs at its forward end in a pivot-box 55 and at its other end in a bearing 56. The pivot-box 55 is fastened to the frame by being bolted at 57 70 through a short transverse slot 58 in the top thereof. This arrangement allows the box 55 to move and gives play to a spring 59 which acts against said box 55 and by so doing holds the friction-pulley 53 firmly 75 against the face of the disk 52. The rear portion of the shaft 54 is made in the shape of a worm 60 and this worm meshes into a worm-wheel 61 on the axle of the driving 80 wheels.

To a loosely fitting collar 62 on the hub of the friction-pulley 53 is attached a loosely fitting collar 63 on the shaft 54. To the sides of the collar 63 are pivoted rods 64 which are also pivoted to the lower end of 85 a lever 65 which in turn is pivoted to a bracket 66 on the frame at 67. As the contact of the friction-pulley is on the face of the disk 52, it will be seen that, although the said disk may be in motion, if the friction-pulley is at the center of said disk, it will not rotate as the upward and downward forces of the face of said disk on the opposite sides of its center will act equally upon the friction-pulley and it will simply 90 slide thereon, but as the lever 65 is brought forward the said pulley is drawn backward and rotates gradually faster until the periphery of the disk is reached when it will have reached its maximum speed forward; 100 if the lever 65 is brought backward the friction-pulley 53 will move forward of the center of the disk and the result will be exactly the reverse with the same gradual increase of speed backward. By this method 105 I can obtain any speed desired up to the maximum, and either forward or backward with equal efficiency.

The surfaces of the grinding-cylinders are covered with some suitable material to 110 form a cushion 68 for the grinding-material 69. This cushion I preferably make of carpeting but as many other materials such as rubber and felt are equally as good I do not wish to limit myself to that selection. 115 The outer or grinding surface of said cylinders consists of sand-paper 69 or some other material having the necessary grinding or abrading quality, the choice of which must necessarily be governed by the material of the floor upon which the cylinders are to operate, and such sand-paper covering is fastened to each of the said cylinders by some suitable means, such as that shown in Figs. 5 and 6, wherein the ends or longitudinal edges of said covering are first inserted in a longitudinal slot 70 in said cylinder, then a rod or wedge 71 pivoted at one end to the corresponding end of said cylinder at 72, is swung down on said pivot 120 125 130

72 engaging the said ends or edges of the grinding material and thereby drawing the said material snugly around the cylinder and wedging the said ends firmly in said slot. The wedge 71 is then fastened in the slot by a latch 73. The said latch is pivoted to the end of the grinding-cylinder and has a nose 74 that fits into a slot 75 in said wedge. This method not only holds the grinding-material firmly but the wedging action of the rod 71 in the slot draws said material tightly and snugly around the cylinder so that a good grinding surface is afforded.

15 I do not intend to limit my invention, in all points, to the precise mechanism shown, and many modifications will readily suggest themselves to one skilled in the art; but

20 What I claim as my invention and desire to secure by Letters-Patent is:—

1. The combination in a floor surfacing machine, of a car, a variable speed friction drive, a grinding-cylinder mounted on said

car, means carried by said car to operate said cylinder, means to operate said friction-drive, and a worm and worm-wheel to transmit motion from the friction-drive to the car.

2. The combination in a floor surfacing machine, of a car, upward spring pressed arms pivoted intermediate their ends thereto, grinding-cylinders mounted on said arms, arm-actuating members slidingly mounted in said car and pivotally attached to said arms, levers to reciprocate said members, a fan, a variable-speed friction-drive, means to operate said fan, means to rotate said cylinders, means to operate said friction-drive from the cylinder operating means, and a worm and worm-wheel to transmit motion from said friction-drive to the car.
